UNITED STATES PATENT OFFICE

159,037

NECKLACE OR SIMILAR ARTICLE

Paul Bardach, Providence, R. I.

Application July 20, 1949, Serial No. 4,013

Term of patent 3½ years

(Cl. D45—16)

To all whom it may concern:

Be it known that I, Paul Bardach, a citizen of the United States, residing at Providence, in the county of Providence and State of Rhode Island, have invented a new, original, and ornamental Design for a Necklace or Similar Article, of which the following is a specification, reference being had to the accompanying drawing, constituting a part hereof.

Fig. 1 is a top plan view of a necklace or similar article showing my new design; and

Fig. 2 is a side view thereof.

I claim:

The ornamental design for a necklace or similar article, substantially as shown.

PAUL BARDACH.
